UNITED STATES PATENT OFFICE

143,634

DESIGN FOR A PIANO

William Zaiser, Rockville Centre, N. Y., assignor to The Rudolph Wurlitzer Company, Chicago, Ill., a corporation

Application October 16, 1944, Serial No. 115,792

Term of patent 3½ years

(Cl. D56—9)

To all whom it may concern:

Be it known that I, William Zaiser, a citizen of the United States, residing at Rockville Centre, in the county of Nassau and State of New York,
have invented a new, original, and ornamental Design for a Piano, of which the following is a specification, reference being had to the accompanying drawings, forming part thereof.

In the drawings:

Fig. 1 is a front elevational view of a piano showing my new design.

Fig. 2 is an end elevational view thereof.

Fig. 3 is a plan view thereof with a portion broken away and wherein the broken away portion is the same as the portion shown in the drawings.

Fig. 4 is a front perspective view of the piano.

I claim:

The ornamental design for a piano, as shown and described.

WILLIAM ZAISER.
